(57) **CLAIM**

The ornamental design for a bottle, as shown and described.

DESCRIPTION

FIG. 1 is a front elevational view of a bottle of the present invention, the rear elevational view being identical except for the threads.

FIG. 2 is a left side front elevational view thereof, the right side elevational view being identical except for the threads.

FIG. 3 is a top plan view thereof; and,

FIG. 4 is a top, front, left side perspective view thereof.

The bottom of the bottle is unornamented and forms no part of the claimed design.

The broken lines shown in the drawings of the inner portion of the pour spout of the bottle are included for the purpose of illustrating environmental structure and form no part of the claimed design.

1 Claim, 4 Drawing Sheets
